Primary Examiner—Wallace R. Burke*Assistant Examiner*—Marcus Jackson*Attorney, Agent, or Firm*—George A. Bode[57] **CLAIM**

The ornamental design for a combined handle and holder for chemiluminescent signal, as shown and described.

DESCRIPTION

FIG. 1 is a rear perspective elevational view of a combined handle and holder for chemiluminescent signal showing my new design;

FIG. 2 is a side elevational view, the side opposite being a mirror image thereof (the top and bottom plan views are identical to the side elevational view);

FIG. 3 is a front elevational view thereof; and,

FIG. 4 is a rear elevational view thereof.

FIG. 3

FIG. 2

FIG. 1

FIG. 4
